CONVERSION OF HYDROCARBON OILS AND GASES

Wayne E. Kuhn, Port Arthur, Tex., assignor to
The Texas Company, New York, N. Y., a corporation of Delaware

Application March 13, 1937, Serial No. 130,620

2 Claims. (Cl. 196—9)

This invention relates to the conversion of hydrocarbon oils and gases and has to do particularly with a combination gas polymerization and oil cracking process in which the gases intended for polymerization are contacted with a hydrocarbon oil to absorb a portion of the gases to aid in the oil cracking process and the mixture of oil and absorbed gases subjected to cracking.

More particularly, according to the invention, a hydrocarbon gas, such as natural or refinery gases, preferably after stabilization, is scrubbed with a suitable cracking stock such as gas oil, crude residuum, heavy naphtha and the like, to absorb a portion of the gases in the cracking stock and the mixture of cracking stock and absorbed hydrocarbon gases is then subjected to cracking conditions of temperature and pressure. The scrubbed gases unabsorbed in the oil may then be subjected to thermal polymerization. The cracking of the mixture of hydrocarbon oil and absorbed gases is intended to involve the principles of gas reversion whereby a larger yield of improved motor fuel products is obtained.

The invention is particularly applicable to the treatment of a refinery gas containing a substantial amount of unsaturated hydrocarbons, whereby the scrubbing operation functions to concentrate or selectively extract the olefins in the hydrocarbon oil. The presence of the olefins in the cracking stock is particularly advantageous, whereby the yield of motor fuel is appreciably increased and formation of undesirable products, such as coke and tars, is decreased. It has been found in this type of operation that the recycle stock from a cracking operation may advantageously be used for the scrubbing of the hydrocarbon gas.

The invention will be more fully understood from the following description taken in connection with the accompanying drawing showing a diagrammatic sketch of one form of apparatus for practicing the invention.

Referring to the drawing, a gas charge which may be natural or refinery gas, or a mixture thereof, is introduced from a suitable source of supply, not shown, through the line 1 and forced by the pump 2 through the line 3 to a fractionator or stabilizer 5. According to the process contemplated by the drawing, the gases are largely in the liquid phase and it is intended that fractionation take place in the stabilizer whereby fixed gases, such as C₁ and C₂ hydrocarbons, are largely separated and withdrawn from the top of the stabilizer through the line 6. It is to be understood, however, that the hydrocarbons may be

mainly in the gaseous phase, in which case the stabilizer 5 may be omitted. The particular type of operation will depend upon the pressures maintained. Under pressures of about 100 pounds or less the hydrocarbons will be largely in a gaseous phase, whereas if a pressure of about 400—600 pounds or above is used, the hydrocarbons will be largely in the liquid phase. The fractionated product, usually consisting predominantly of C₃ and C₄ hydrocarbons, is withdrawn from the bottom of the stabilizer 5 through the line 7 and forced by the pump 8 through the line 9 to an absorber 10. In this absorber the gases pass countercurrent to a scrubbing oil which may be a cracking stock introduced through the line 12 and forced by the pump 13 wholly or in part through the line 14 to the top of the scrubber. In case all of the oil is not charged to the absorber, the remainder may be passed through the line 15 directly to the cracking coil 16, referred to hereinafter. In the absorber 10, a substantial amount of the gaseous hydrocarbons is absorbed in the scrubbing oil, and in case the gases are high in olefin content, it has been found that the olefins are preferentially absorbed by the oil. It is intended that about 5—20%, and preferably about 10%, of the gaseous hydrocarbons may be absorbed. The conditions maintained in the absorber 10 may be about the same as those maintained in the stabilizer 5.

The oil containing the absorbed gaseous hydrocarbons is withdrawn from the bottom of the absorber through the line 18 and forced by the pump 19 to the cracking coil 16 located in a furnace 20. In the cracking coil 16 a mixture of oil and absorbed gases is subjected to rather drastic conditions of temperature and pressure. These conditions may be about 500—1000 pounds pressure and about 900—1050° F., preferably around 950—1000° F. The cracked products are transferred from heating coil 16 through the line 21 to a reaction chamber 22. A large proportion of the materials is vaporized, that proportion unvaporized dropping through the reaction chamber and continuously withdrawn through the draw-off line 24 at the bottom of the chamber. Vapors and gases pass through the vapor line 25 to a fractionator 26. In the latter fractionator substantially all the products of higher boiling point than gasoline are fractionated and condensed out, the uncondensed gases passing overhead through the vapor line 28 and condenser 29 to an accumulator 30. The reflux condensate or recycle stock condensing out in fractionator 26 is drawn through a line 32 and recycled by the pump 33 to

the heating coil 16. In some cases, particularly when the gaseous charge is high in olefin content, it is desirable to use all or a portion of this recycle stock as a scrubbing medium, and for this purpose, the recycle stock may be passed through the branch line 34 to the upper portion of the absorber 10. This recycle stock is often effective for selectively extracting the olefins from the gas. The product collecting in the accumulator 30 is a gasoline usually of high antiknock quality. This product may be withdrawn from the accumulator through the draw-off line 36 while the uncondensed gaseous hydrocarbons may be released from the top of the accumulator through the line 37.

The gaseous hydrocarbons unabsorbed by the oil in the absorber 10 are withdrawn from the upper portion of the absorber through the line 43 and forced by pump 41 to a polymerization coil 42, located in a furnace 44. These gases are usually relatively high in paraffin content and are suitable for thermal polymerization. The polymerizing conditions maintained in coil 42 are the conventional conditions used for thermal polymerization, such as pressures from 500-5000 pounds and temperatures of 900-1100° F., and preferably pressures of around 1000-2500 pounds and temperatures of about 1020-1070° F. The polymerization products are transferred through the line 45 in which may be located a transfer line heat exchanger or other cooling means, to a fractionator 46. In this fractionator the high boiling hydrocarbons, such as tars, are condensed and withdrawn from the bottom thereof through the line 48. The uncondensed vapors and gases are conducted from the top of the fractionator 46 through the line 49 to a secondary fractionator 50. In the fractionator 50 the normally liquid hydrocarbons usually of gasoline boiling range, are condensed and fractionated out and withdrawn from the bottom thereof, through the line 51. The intermediate boiling point fraction containing a large proportion of C₃ and C₄ hydrocarbons may be withdrawn from an intermediate point in the fractionator 50 through the line 53 and recycled by the pump 54 to the polymerization coil. The unpolymerized gases are withdrawn from the top of the fractionator 50 and these gases together with those withdrawn from the top of the accumulator 30 may be returned through the line 56 in which is located pump 57, to the stabilizer 5 to be retreated in the system.

As an example of the operation of the invention, cracking still gases containing about 20-30% unsaturated constituents were scrubbed with recycle stock from a cracking system, operating on a recycle basis. Charge rates were maintained so that approximately 10% of the gases was absorbed. The mixture of oil and absorbed gases was charged to a cracking coil wherein cracking conditions of about 750 pounds and about 975° F. were maintained. About 6-7% increase in yield of gasoline was obtained in the cracking operation over that which would normally be obtained without the presence of the absorbed gases. The gasoline also had an increased antiknock value of 2 or 3 points and a better grade of fuel oil and less coke were pro-

duced. The scrubbed gases are subjected to thermal polymerization at 2000 pounds pressure and about 1050° F., and a time of reaction of about 40 seconds. In addition, about 50-60% of the scrubbed gases is converted into liquid products in the polymerization operation.

Obviously many modifications and variations of the invention, as hereinbefore set forth, may be made without departing from the spirit and scope thereof and therefore only such limitations should be imposed as are indicated in the appended claims.

I claim:

1. A process for the conversion of hydrocarbon oils and gases into gasoline, which comprises subjecting a fresh charging stock consisting essentially of normally gaseous hydrocarbons of the class of natural and refinery gases to stabilization to separate therefrom fixed gases lighter than C₃ hydrocarbons, scrubbing the remaining gases with a hydrocarbon oil cracking stock to absorb a portion of the higher boiling saturated and unsaturated constituents, subjecting unabsorbed gases to a separate polymerization operation in the absence of combustion gases at temperatures and pressures sufficient to form a maximum amount of aliphatic polymers boiling within the gasoline boiling point range, separating said polymers from unpolymerized gases, subjecting the mixture of cracking stock and absorbed gases to a separate conversion operation at temperatures sufficient to effect conversion thereof into gasoline, separating a gasoline fraction and a residual gaseous fraction from the cracked products, and recycling said residual gaseous fraction from the cracking operation and said unpolymerized gases from the polymerization operation to said stabilization operation.

2. A process for the conversion of hydrocarbon oils and gases into gasoline, which comprises subjecting a fresh charging stock, consisting essentially of normally gaseous hydrocarbons of the class of natural and refinery gases, to a stabilizing operation by substantially removing therefrom the fixed gases lighter than C₃ hydrocarbons, then subjecting the remaining gases to an absorption operation by contacting therewith a hydrocarbon oil cracking stock whereby a portion of higher boiling saturated and unsaturated constituents of the gases is absorbed by said cracking stock, subjecting the unabsorbed gases from the absorption operation to a separate polymerizing operation in the absence of combustion gases under pressures of about 500 to 5000 pounds and temperatures of about 900 to 1100° F. whereby normally liquid hydrocarbons essentially of aliphatic character are formed, separating said normally liquid hydrocarbons from unpolymerized gases, subjecting the mixture of cracking stock and absorbed gases to a separate conversion operation at temperatures sufficient to effect conversion of the cracking stock and gases into gasoline, separating gasoline and residual gases from the cracked products and recycling said residual gases from the cracking operation and said unpolymerized gases from the polymerization operation to said stabilizing operation.

WAYNE E. KUHN.
